ELECTRICAL RELAY

Herman G. Blosser, Pittsburgh, Pa., assignor to
The Union Switch & Signal Company, Swiss-
vale, Pa., a corporation of Pennsylvania

Application September 4, 1943, Serial No. 501,231

7 Claims. (Cl. 172—126)

My invention relates to electrical relays, and particularly to electrical relays which are suitable for use in railway signaling systems employing for the control of signaling devices direct current which is periodically interrupted or coded at different frequencies in accordance with traffic conditions.

More particularly, my present invention relates to relays of the type described in Letters Patent of the United States No. 2,300,790, granted to Robert M. Laurenson on November 3, 1942, in which the rate of operation of the relay when the relay is energized is determined by the period of oscillation of a relatively massive compound pendulum, and one object of my present invention is to provide an improved bearing for supporting the pendulum in relays of the type disclosed in said patent, which bearing shall have negligible friction and extremely long life.

Another object of my invention is to provide a bearing for supporting the pendulum in relays of the type described which bearing can be manufactured more cheaply than bearings of the type heretofore employed.

According to my invention, the bearing comprises a horizontal flat surface formed on the pendulum and arranged to roll on a cylindrical supporting surface formed on a cooperating bearing member. The positioning of the pendulum with respect to the supporting member is maintained by conical pins secured to the pendulum and cooperating with conical holes formed in the bearing member.

Other objects and characteristic features of my invention will become apparent as the description proceeds.

I shall describe one form of electrical relay embodying my invention, and shall then point out the novel features thereof in claims.

In the accompanying drawings, Fig. 1 is a vertical sectional view showing one form of relay embodying my invention. Fig. 2 is a left-hand side view of the relay shown in Fig. 1. Fig. 3 is a detail sectional view taken on the line III—III of Fig. 2.

Similar reference characters refer to similar parts in all three views.

Referring to the drawings, the relay here shown is generally similar to the relay described and claimed in the aforementioned Laurenson Patent No. 2,300,790 except for the bearing means presently to be described for supporting the compound pendulum of the relay.

The relay as shown comprises a contact carrying rocker 1 of suitable insulating material, such as a phenol condensation product, suspended by

means of flexible strips 2 from a top plate 3, also of suitable insulating material. The rocker 1 is provided with a plurality of flexible contact fingers 4 and 5, each of which cooperates with a fixed contact member 4a or 5a to close a contact 4—4a or 5—5a according as the rocker is swung to one or the other of its extreme positions. The contacts are disposed in pairs and are secured to the opposite sides of the rocker within vertical grooves which maintain the fingers in the desired vertical position, by means of studs 6 moulded into the rocker and provided at each end with a nut 7. The studs 6 also serve to secure the lower ends of the strips 2 to the rocker, thereby electrically connecting the fingers with the strips. The upper ends of the strips are secured to the heads of terminal posts 8 mounted on the top plate 3. The positions of the flexible fingers when the fingers are out of engagement with the associated fixed contact members are determined by means of stops 9 which are clamped against the outer faces of the fingers by means of the associated studs 6, and which are so adjusted by bending them that the fingers will break the contacts in the desired positions in response to the swinging movement of the contact carrying rocker 1.

The fixed contact members 4a and 5a are similar to the fixed contact members 18a and 18b described and claimed in Letters Patent of the United States No. 2,285,890, granted to me on June 9, 1942, for Electrical relays, and are adjustably secured to the lower ends of terminal studs 10 mounted on the top plate on opposite sides of the terminal posts 8 in a manner which is similar to that described in the said patent. It is believed to be unnecessary, therefore, to describe the construction and arrangement of these fixed contact members any further herein.

The relay also comprises motor means for oscillating the rocker between its two extreme positions to alternately operate the contacts at a constant relatively low preselected frequency. As here shown, this motor means consists of an electromagnet C having pole pieces 11a and 11b secured by means of studs 12 to the plate portions 13a and 13b of a frame 13 in parallel spaced relation and connected together at one end by a core 14 surrounded by a winding 15.

The frame 13 is suspended from the top plate 3, and has its main or upper part formed from a single piece of material bent generally into an inverted U-shape. The plate portions 13a and 13b are of substantially trapezoidal form and terminate at their upper ends in spaced parallel arms 13c which form openings 13d through which

certain portions of the contact mechanism of the relay can be viewed for inspection. Intermediate their ends the plate portions 13a and 13b are clamped together by means of studs 16 passing through clearance holes in the plate portions and screwed into tapped holes provided in the opposite ends of a bearing member 17 which also serves as a spacing member. It will be seen, therefore, that the frame provides a rigid support for the electromagnet C.

The pole pieces 11a and 11b of electromagnet C cooperate at their low or free ends with a magnetizable armature 18 which is secured to one side of the lower portion or foot of a compound pendulum P.

The compound pendulum P may have any suitable form possessing within the limited space available the necessary mass to cause it to have a natural period equal to the desired code frequency, which may, for example, be 75 cycles per minute. In the form here illustrated, this pendulum comprises a casting consisting of a central horizontal portion 20 provided at its opposite ends with upstanding arms 20a, and provided intermediate its ends at one side of said horizontal portion with a central depending leg 20b terminating at its lower end in a foot 20c to which the armature 18 referred to hereinbefore is secured.

The lower surface 20d of the horizontal portion 20 serves as a bearing surface and rests on the bearing member 17. The bearing member 17 is cylindrical in shape except for a recess 17a formed in one side thereof opposite the leg 20b to provide clearance for the leg when the pendulum is oscillating, and the surface 20d is made flat. It will be seen therefore that oscillation of the pendulum will cause the flat surface 20d to roll around the upper curved surface of the bearing member in such manner that a new line of contact is formed in each different angular position of the pendulum throughout its entire angular movement. The pendulum is maintained in the desired longitudinal and lateral position relative to the bearing member by means of longitudinally spaced positioning pins 21 provided with conical heads 21a which cooperate with the conical upper ends of vertical holes 22 provided in the bearing member 17. As shown the pins are secured to the portion 20 of the pendulum at two locations at the center of the pendulum movement. These pins can, however, be placed at any location to definitely establish the position of the pendulum with respect to the cylindrical surface.

The pendulum P is operatively connected with the rocker 1 through the medium of an arm 25 the upper end of which is secured to the center of the rocker by means of one of the studs 6. The lower end of this arm is provided with bifurcations 25a which straddle a transverse cylindrical driving rod 28 mounted at its ends in aligned holes 29a provided in the enlarged upper ends 20a of the pendulum P. The parts are so proportioned that oscillation of the pendulum P will cause one or the other of the bifurcations to engage the driving rod in a line contact without binding in any position of the pendulum.

With the pendulum operatively connected with the rocker in the manner just described it will be apparent that rotation of the pendulum in one direction will cause swinging movement of the rocker in the opposite direction, and the parts are so proportioned that oscillation of the pendulum through its normal amplitude will cause movement of the rocker between its two extreme positions. The weight of the pendulum assisted

by the friction of the bearing surfaces to sliding motion normally acts to keep the pendulum from moving to positions in which the pins 21a are out of alignment with the cooperating conical holes. However, excessive movement of the pendulum is also prevented by the arm 25 and driving pin 28.

The length of the pendulum P is such that the armature 18 is free to swing between the pole pieces 11a and 11b, and it will be seen, therefore, that energization of the winding 15 will tend to pull the armature 18 between the pole pieces and hence will swing the rocker in a clockwise direction, as viewed in Fig. 1. The energization of the winding 15 may be controlled by one set of the contacts 4-4a and 5-5a connected in series with the winding and adjusted so that both contacts are closed when the pendulum occupies its gravity biased position but that when the pendulum is swung away from this position one or the other of these contacts will become opened at a predetermined intermediate point in the stroke of the pendulum depending upon which direction the pendulum is swung.

It will be obvious that oscillation of the pendulum will cause the contacts 4-4a and 5-5a which are not used to control the energization of the winding 15 to be alternately opened and closed at the frequency of oscillation of the pendulum. These contacts may be used for coding purposes as will be readily understood.

One advantage of a bearing structure embodying my invention is that the friction between the bearing parts is negligible as shown by the fact that if the pendulum is released from a given maximum position and allowed to coast to a standstill the contacts on either side of the rocker will become alternately opened and closed for approximately 135 times before the amplitude of the oscillation decreases to the point where the contacts are no longer operated. This is several times the number of contact operations that can be obtained under similar conditions with bearings of the types heretofore employed.

Another advantage of a bearing structure embodying my invention is that on the pendulum proper there are no wearing parts and no spring suspension which may become overstressed with excessive travel.

A further advantage of a bearing structure embodying my invention is that it enables the operative connection between the pendulum and the contact carrying rocker to be simplified.

A still further advantage of a bearing structure embodying my invention is that the bearing parts are easy to machine and assemble, so that the cost of the bearing is a minimum.

Although I have herein shown and described only one form of electrical relay embodying my invention, it is understood that various changes and modifications may be made therein within the scope of the appended claims without departing from the spirit and scope of my invention.

Having thus described my invention, what I claim is:

1. In combination, a horizontal bearing member having a flat cylindrical surface, a compound pendulum provided with a flat surface resting on said bearing member in such manner that it is free to roll around said cylindrical surface in response to oscillation of said pendulum, and means for positioning said pendulum relative to said bearing member comprising a conical pin in one part cooperating with a conical hole provided in the other part.

2. In combination, a horizontal bearing member having a cylindrical surface and provided with two longitudinally spaced vertically disposed conical holes, a compound pendulum provided with a flat surface resting on said bearing member in such manner that said flat surface is free to roll around said cylindrical surface in response to oscillation of said pendulum, and a pair of conical pins secured to said pendulum and cooperating with said conical holes to position said pendulum relative to said bearing member.
3. In combination, a horizontal bearing member having a cylindrical surface, a compound pendulum comprising a central horizontal portion provided at its opposite ends with upstanding arms and provided intermediate its ends with a central depending leg terminating at its lower end in a foot, the underside of said horizontal portion being provided with a flat surface which rests on said bearing member in such manner that it is free to roll on said cylindrical surface in response to oscillation of said pendulum, and a pair of conical pins secured to said central portion and cooperating with the conical holes in said bearing member to position said pendulum relative to said bearing member.
4. In combination, a horizontal bearing member having a cylindrical surface, a compound pendulum comprising a central horizontal portion provided at its opposite ends with upstanding arms and provided intermediate its ends with a central depending leg terminating at its lower end in a foot, the underside of said horizontal portion being provided with a flat surface which rests on said bearing member in such manner that it is free to roll on said cylindrical surface in response to oscillation of said pendulum, and means on said horizontal portion cooperating with means on said bearing member to position said pendulum relative to said bearing member.
5. In combination, a horizontal bearing member having a cylindrical surface, a compound pendulum comprising a central horizontal portion provided at its opposite ends with upstanding arms and provided intermediate its ends with a central depending leg terminating at its lower end in a foot, the underside of said horizontal portion being provided with a flat surface which rests on said bearing member in such manner that it is free to roll on said cylindrical surface in response to oscillation of said pendulum, a pair of conical pins secured to said central portion and cooperating with the conical holes in said bearing member to position said pendulum relative to said bearing member, an armature secured to said foot, an electromagnet cooperating with said armature to cause oscillation of said pendulum, a contact carrying rocker mounted above said pendulum, a depending arm secured to said rocker and provided with a bifurcated lower end, and a transversely extending driving rod mounted at its ends in said upstanding arms and extending intermediate its ends between said bifurcations to operatively connect said pendulum with said rocker.
6. In combination, a horizontal bearing member having a cylindrical surface, a compound pendulum comprising a central horizontal portion provided at its opposite ends with upstanding arms and provided intermediate its ends with a central depending leg terminating at its lower end in a foot, the underside of said horizontal portion being provided with a flat surface which rests on said bearing member in such manner that it is free to roll on said cylindrical surface in response to oscillation of said pendulum, a pair of conical pins secured to said central portion and cooperating with the conical holes in said bearing member to position said pendulum relative to said bearing member, an armature secured to said foot, an electromagnet cooperating with said armature to cause oscillation of said pendulum, a contact carrying rocker mounted above said pendulum, a depending arm secured to said rocker and provided with a bifurcated lower end, and a transversely extending driving rod mounted at its ends in said upstanding arms and extending intermediate its ends between said bifurcations to operatively connect said pendulum with said rocker, the parts being so proportioned that said rod cooperates with said arm to limit vertical displacement of said pendulum.
7. In combination, a horizontal bearing member having a cylindrical surface, a compound pendulum provided with a flat surface resting on said bearing member in such manner that it is free to roll around said cylindrical surface in response to oscillation of said pendulum, and means for positioning said pendulum relative to said bearing member.
